[57] CLAIM

The ornamental design for a mask for supporting and displaying mammography film, as shown and described.

DESCRIPTION

FIG. 1 is a perspective view of a mask for supporting and displaying mammography film showing our new design; FIG. 2 is a front elevational view thereof;

FIG. 3 is an end view thereof;

FIG. 4 is a rear elevational view thereof; and,

FIG. 5 is a top end view.

The top and bottom portions of the mask are solid and opaque to light and are indicated on the drawings in cross-hatch.
